UNITED STATES PATENT OFFICE.

JOHN GILMOUR, OF OWENSBORO, KENTUCKY, ASSIGNOR TO GILMOUR HOGSHEAD MACHINE COMPANY, OF OWENSBORO, KENTUCKY, A CORPORATION OF KENTUCKY.

WIRE HOOP AND CRATING MACHINE.

1,411,488.

Specification of Letters Patent.

Patented Apr. 4, 1922.

Application filed June 19, 1919, Serial No. 305,353. Renewed January 4, 1922. Serial No. 527,057.

To all whom it may concern:

Be it known that I, JOHN GILMOUR, a citizen of the United States, resident of Owensboro, in the county of Daviess and State of Kentucky, have made a certain new and useful Invention in Wire Hoop and Crating Machine; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a side view or edge view of the invention.

Figure 2 is a face view of the same.

Figure 3 is a detail edge or side view of a clamp lever.

20 Figure 4 is a detail inner face view of the same.

Figure 5 is a detail face view of the free end of one of the branches of the invention.

Figure 6 is a detail edge view of the same, 25 showing also the screw and the washer.

The invention has relation to improved means for applying wire hoops to casks and crates in making them up into form, and it 30 consists in the novel construction and combinations of parts, as hereinafter set forth.

In the accompanying drawings illustrating the invention, the numeral 2 designates a portion of a cask or crate around which is passed the wire 3, the lapping ends of said 35 wire being shown as releasably engaged or clamped to the branches 4 of the tool or implement, said branches being pivoted together at one end at 5.

The branches or arms 4 are each longitudinally bowed and lapped at their pivotal portions at 6 which are located in different planes, being then bent or brought towards each other so as to be located in the same plane throughout intermediate portions of 45 the lengths of the said arms, in order that the stretching means or screw 7 engaging said intermediate portions shall be adapted to exercise its function more perfectly; the opposite or free ends of said arms being bent 50 outwardly so that they are located in different planes whereby the lapping ends of the

binding wire engaged by said free ends are adapted to pass each other.

The free ends of the arms 4 are provided with lugs or offsets 8, extending laterally in opposite directions and provided each with a groove 9 which is preferably arcuate, so that when the clamping levers 10 engage the lapped ends of the wires, said ends will be pressed downwardly into engagement with 55 said grooves to form a bend in the wire ends and better hold the wires in place while the stretching operation is going on.

The levers 10 are provided with toothed inserts 11, which have wedge form and are 60 let into wedge form seats or notches 12 of the levers from the inner side of the latter, so that when the levers have their perforations 13 engaged with the pivot pins 14, said 65 inserts will be securely held in place being prevented from lateral movement in either direction. The clamping levers are provided with marginal flanges 15 on their work arms or ends, said flanges lapping over the grooved wire-supporting lugs or offsets 8 and guarding the lapped wire ends from escape from the grooves of said offsets, also guarding the fingers of the operator from being caught and pinched between the levers and offsets.

The intermediate portions of the arms or 70 branches 4, are provided with pivotal blocks 16, the pivot pins of which engage perforations of said branches and of brackets 17 secured to the branches, said blocks being oppositely screw threaded and engaged by the 75 oppositely screw threaded portions of the screw rod 18, so that when the latter is operated by the hand wheel 19, the branches of the tool or device will be powerfully forced apart to exert tension upon the lapped ends 80 of the binding wire and draw together or into form the staves or parts of the cask or crate being made up.

The pivot pins 14 of the clamping levers are usually or preferably fast to the branches 95 4 of the tool, and provided with threaded seats in their outer ends engaged by the fastening screws 20, a lock washer 21, being an ordinary spring split washer inserted between the heads of said screws and the levers 10, so that the working of the levers 100 will be prevented from causing the fastening

screws to work loose. The levers 10 are preferably provided with apertures 22, leading to the wedge form seats 12 whereby the toothed inserts may be more readily knocked 5 out or removed from said seats when renewal is required.

In the operation of this device, it is grasped by the pivotal end thereof throughout the stretching operation, and in order to facilitate its management and to prevent the fingers of the operator from being caught and pinched when the branches of the tool are drawn together in use, the pivotal ends are made of arcuate or approximately semi-circular form, matching each other to provide 10 always a hand-hold opening 23.

This device has been found very useful in practice in the assemblage of casks and crates quickly and with little labor, and is 15 readily operable by an unskilled person.

After the tightening of the hoop is completed, the device as a whole is given a one-half turn, and the ends of the hoop secured 20

to the cask or crate by staples, the operation being then completed, ready for the release 25 of the cam levers.

I claim:—

In a device for applying wire hoops to casks and crates, an arm having a laterally extending wire-supporting lug provided with 30 an arcuate groove, a clamping lever fulcrumed to one side of said arm and provided with a marginal flange overlapping the outer edge of said lug and having a wedge-form seat opening towards and closed by a 35 lateral surface of said arm, and a wedge-form toothed insert fitting within said seat, said lateral surface of said arm holding said insert in place.

In testimony whereof I affix my signature, 40
in presence of two witnesses.

JOHN GILMOUR.
